(57) CLAIM

We claim the ornamental design for a washing machine displaying graphical user interface, as shown.

DESCRIPTION

The patent or application file contains at least one drawing executed in color. Copies of this patent or patent application publication with color drawing(s) will be provided by the Office upon request and payment of the necessary fee.

FIG. 1 is a front view of a washing machine displaying graphical user interface showing our new design;

FIG. 2 is a front view of a washing machine displaying graphical user interface showing an alternate embodiment of our new design;

FIG. 3 is an enlarged front view of the graphical user interface of FIG. 1; and,

FIG. 4 is an enlarged front view of the graphical user interface of FIG. 2.

The broken lines shown in FIGS. 1 and 2 are for the purpose of illustrating structure that is not part of the claimed design, but is considered necessary to show the environment in which the design is associated and forms no part of the claimed design.
